FIG. 1 is a top plan view of a calculator for carton-board price and footage showing my new design.

FIG. 2 is an end view taken along line 2—2 of FIG. 1.

FIG. 3 is a bottom plan view.

FIG. 4 is a partial sectional view taken along line 4—4 of FIG. 2.

FIG. 5 is a partial sectional view taken along line 5—5 of FIG. 2.

FIG. 2.

I claim:

The ornamental design for a calculator for cartonboard price and footage, substantially as shown and described.
